SHIPPING CONTAINER

Philip F. Paul, North Hollywood, and Louis O'Leary, Los Angeles, Calif., assignors to The Patent and Licensing Corporation, New York, N. Y., a corporation of Massachusetts

Application March 10, 1950, Serial No. 148,968

1 Claim. (Cl. 229—23)

1 This invention relates to containers and more particularly to a fiberboard container of the open top type intended for use in packing and shipment of a variety of commodities.

In the packing and shipment of certain commodities, such for example, as hands of bananas, it is desirable that the container be of the open top type. With such open top containers the problem of stacking loaded containers during storage and shipment requires not only that the container have adequate vertical compressive strength and resistance to lateral collapse, but that it be constructed in such a way as to prevent any superposed container in a stack from falling into the container immediately therebelow in the stack.

An object of the invention is to provide a fiberboard container suitable for use, as above stated, as an open top container and constructed to enable the containers to be stacked on one another without danger of an upper container falling into a lower one in the stack.

Another object of the invention is to provide a container of the character set forth and possessing sufficient vertical compressive strength particularly at the corners of the container, to enable it to withstand relatively heavy compression loads to which it may be subjected in use.

Still another object of the invention is to provide a container as aforesaid which, for a given cubical capacity, can be made from an amount of sheet material less than required by previously known forms of containers that can serve these purposes.

The container embodying the invention comprises a one-piece, rectangular bottom wall, a pair of opposed, rectangular side walls and a pair of opposed end walls of trapezoidal shape, the base of the trapezoid constituting the lower end of these walls, and the upper end of the trapezoid constituting the upper edge of the end walls and lying in substantially the same plane as the upper edges of the side walls. In this manner, the container is provided with an open top of rectangular form but of substantially smaller surface area than that of the bottom wall. Hence, when one container is superposed on another, the bottom of the upper container will overhang the side walls of the container therebelow and be thereby supported against falling into the latter. In order to insure against this contingency, and further to strengthen the container, the end walls are provided with integral extensions which may be positioned to form a relatively narrow platform at each end of the container, these plat-

2 forms resting upon the upper edges of the side walls in a plane parallel to the bottom of the container and being long enough to overhang the side walls of the container a substantial distance. The platforms are provided with flaps receivable in slots formed along the upper edges of the side walls so as not only to retain the platforms in proper position, but also to impart increased rigidity and strength at the ends of the container by reason of the resultant truss effect.

The invention and the features and advantages thereof will be more clearly understood from the accompanying drawings, in which:

Fig. 1 is a perspective view of a container embodying the invention;

Fig. 2 is a fragmentary view, in perspective, showing one end of the container, with one of the parts removed from position;

Fig. 3 is a fragmentary detailed view, partly in section, of one end of the container;

Fig. 4 is a plan view of a blank for forming the end walls of the container shown in Fig. 1; and

Fig. 5 is a plan view of a blank for forming the bottom and side walls thereof.

The preferred form of container embodying the invention, may be made from corrugated fiberboard, or the like, and comprises a bottom 11, side walls 13 and end walls 16.

The bottom 11 and side walls 13 are each of rectangular outline and are preferably formed integrally with one another from a single piece blank indicated generally by the numeral 17 in Fig. 5.

The end walls 16 are of trapezoidal outline, the side edges 20 thereof extending at equal angles with respect to the base 22, and the base 22 being of a length substantially equal to the width of the bottom wall 11. The upper ends of the walls 16 are of a length approximately two inches less than that of the lower ends thereof.

Hinged flaps 21 formed at opposite ends of the bottom wall 11 may be stitched or stapled as indicated at 25 to the lower marginal portion of the end walls 16 and hinged flaps 23 formed at opposite ends of each of the side walls 13 may be similarly fastened, as indicated at 27, to the marginal sides of the end walls. The securing of the end walls to the bottom and side walls by means of the flaps 21, 23 provide vertical strength at the corners of the container. As will be seen in Figs. 1 and 2, the side walls 13 lie in planes extending upwardly and inwardly with respect to the bottom wall 11 at angles depending upon the angle of inclination of the side edges 20 of the end walls. The open top of the container is thus

3

of considerably less width than the bottom 11, so that when stacked one on another the bottom of one container overhangs the side walls of the container therebeneath. In this manner, an upper container is prevented from falling into the 5 one below it in the stack and causing not only disruption of the stack but damage to the contents of the lower container.

To insure further against any such occurrence, the end walls 16 are each provided with a hinged 10 integral extension 26, which may be folded at right angles to the end walls, to provide a relatively narrow platform at each end of the container. As will be noted, these platforms are supported by the upper edges of the side walls. In 15 this position they constitute additional bearing surface at each end of the container for a superposed container in a stack. The platforms 26 are secured in that position by a hinged flap 30 integral with each platform and inserted in 20 transversely aligned slots 33, 35 formed along the upper edges of the side walls 13. The platforms 26 and flaps 30 are each of a length substantially 25 equal to that of the bottom edge of the end walls so as to extend a substantial distance laterally 30 in opposite directions beyond the upper edges of the side walls. It will be noted that when platforms 26 are brought from the position shown in Fig. 2 to that shown in Fig. 1 wherein they rest upon the upper edges of the side walls and wherein the flaps 30 are held within slots 33, 35, a truss effect is obtained which contributes greatly to the vertical compressive strength at the vertical corners of the container.

Hand holes 36 are formed in each of the end 35 walls 16 by partially cutting a flap 38, left connected to the end walls along the upper edge of holes. The hand holes 36 are positioned at a distance below the upper edges of the end walls such that when the fingers of one's hand are extended 40 through the holes, the hand will grip around the platforms 26.

We claim:

An open-top, fiberboard shipping container for 45 bananas and like commodities, comprising a rectangular bottom portion, inwardly inclined rec-

4

tangular longitudinal side walls integral with said bottom portion, a pair of end wall members having side edges inclined inwardly and upwardly, said bottom portion and said longitudinal side walls having inwardly turned flaps on their end edges and said flaps being secured to the marginal portions of the said end walls to provide a container having a rectangular open top of substantially lesser area than the area of said rectangular bottom portion, and integral extensions on the upper edges of said end walls bent inwardly to overlie the free upper edges of the longitudinal side walls in a plane parallel to the plane of the said bottom portion, said integral extensions extending laterally outwardly substantially beyond the upper ends of said side walls, the upper edges of said side walls being provided with downwardly-extending transversely-aligned slots adjacent each end wall and said integral extensions having downwardly-extending integral flaps received in said aligned slots of the side walls.

PHILIP F. PAUL.
LOUIS O'LEARY.
